UNITED STATES PATENT OFFICE

LEONARD CHESTEEN WOOD, OF ALDEN, IOWA

ROAD GRADER

Application filed June 17, 1929. Serial No. 371,469.

This invention relates to improvements in road graders of that type having a supporting frame carried by front and rear wheels, and a scraper blade arranged beneath the frame between the front and rear wheels, and adapted to be adjusted to various angles relative to the advance of the grader, and to have its ends adjusted independently to various elevations.

10 Heretofore considerable difficulty has been experienced in providing suitable mechanism for supporting the scraper blade in its various adjusted positions of movement, and in connection therewith means which may be 15 easily operated manually for adjusting the blade in its various positions of movement, and at the same time providing mechanism which is rigid in construction and which will rigidly and positively support the scraper 20 blade in its working positions.

It is therefore the object of my invention to provide in a grader improved means of simple, durable and inexpensive construction for rigidly supporting the scraper blade 25 in various adjusted positions of movement, and at the same time permit the blade to be easily and quickly adjusted.

A further object is to provide a mechanism 30 for supporting and controlling the scraper blade, the weight of which is entirely carried by the grader frame and entirely eliminated from the scraper blade itself, whereby the scraper blade may be elevated with a minimum amount of power, and to provide 35 in connection therewith improved means whereby the scraper blade will be caused to enter the ground with a minimum amount of manually applied power.

40 A further object is to provide in a grader of the type above described, improved means for applying the power from the scraper frame to the blade, whereby auxiliary weight applied to the blade for the purpose of causing it to enter the ground is eliminated.

45 A further object is to so mount the mechanism for supporting and controlling the scraper blade above and upon the grader frame, whereby a maximum amount of clearance may be provided between the under surface of the scraper frame and the upper edge

of the scraper blade, and to provide a large amount of clearance between the scraper blade and the front wheels and the under surface of the scraper frame.

50 A further object is to provide improved means for independently elevating and lowering the ends of the scraper blade.

55 My invention consists in the construction, arrangement and combination of the various parts of the device, whereby the objects contemplated are attained, as hereinafter more fully set forth, pointed out in my claims, and illustrated in the accompanying drawings, in which:

60 Figure 1 is a side elevation of my improved grader.

65 Figure 2 is a transverse sectional view taken on the line 2—2 of Figure 1.

70 Figure 3 is a central sectional view taken through the scraper supporting head and through a portion of the mechanism for elevating and lowering the blade, the said scraper supporting head being illustrated in a position 90° from the position illustrated in Figures 1 and 2.

75 Figure 4 is a top view of the scraper supporting head and the arms for elevating and lowering the scraper blade.

80 Figure 5 is a segmental detail sectional view taken on the line 5—5 of Figure 2.

85 Figure 6 is a rear elevation of the manually operated devices for controlling the scraper blade.

Figure 7 is an enlarged, detail, sectional view taken on the line 7—7 of Figure 6.

90 My improved grader comprises a pair of frame members 10 having their forward ends supported by a truck 11, which in turn is supported by the wheels 12 and provided with a stub tongue 13, by means of which the device is drawn over the ground surface and steered.

95 The frame members 10 incline outwardly and rearwardly and have their rear ends supported by an axle 14 carried by wheels 15. Each of the side members 10 is provided with a downwardly extending flange 16 connected by a brace member 17. The lower edges of the flanges 16 terminate a considerable dis-

tance above the ground surface, as illustrated in Figure 1.

Supported on top of the members 10, slightly back of the center of the frame, is a plate 18. A similar plate 19 is supported adjacent to the under edges of the frame members 10 and beneath the plate 18.

Supported in the plates 18 and 19 is an upright shaft 20 firmly anchored in said plates, 10 and having one end projecting above the frame members 10 a considerable distance. The shaft 20 is designed to rotatively support what I shall term the scraper blade supporting head 21. The lower end of the head 15 21 is provided with a disk 22, which may be detachably secured to said head by means of bolts or rivets 23. A washer 24 is provided to rest on top of the plate 18 and on which the head 21 is rotatively mounted.

20 The disk 22 is provided with a series of holes 25 near its periphery, designed to receive a locking pin 26 slidably mounted vertically in the plates 18 and 19, and designed to have its upper end project upwardly into 25 one of the openings 25 to provide means for locking the said head 21 in various angular positions of movement about the shaft 20.

The pin 26 is provided with an opening 30 through which a rock arm 27 has one end projected, said rock arm being mounted in a rock shaft 28, rotatively mounted in the members 10 and back of the shaft 20. One end of the shaft 28 is provided with a lever 29 supported outside of the frame member 10. A 35 spring 30 is provided having one end anchored to the member 10 and its other end to the lever 29, in such a manner that if the free end of the lever 29 is elevated or lowered, the spring will yieldably retain the lever in either 40 of said positions, causing the shaft 28 to be rocked and in turn the arm 27, and the slide pin 26 to be elevated or lowered.

The head 21 is provided with oppositely arranged and laterally projecting arms 31 45 adapted to be normally supported transversely above the frame members 10. Each of the arms 31 is provided with bearing members 32 and 33. One set of bearing members 32 and 33 is designed to rotatively receive a 50 screw threaded shaft 34, while the other set of bearings is designed to rotatively receive a screw threaded shaft 35, one of the shafts being screw threaded in the opposite direction from the other.

55 The inner end of the shaft 34 is provided with a bevel gear 36 in mesh with a bevel gear 37 rotatively mounted on a contracted portion 38 of the shaft 20. The bevel gear 37 has an upwardly extending hub 39. A 60 bevel gear 40 is also rotatively mounted on the portion 38 and has a downwardly extending hub designed to rest adjacent to the hub 39.

Pins 41 are provided for uniting the hubs 65 of the two gears 37 and 40 to form a sleeve.

The bevel gear 40 is in mesh with a bevel gear 42 rotatively mounted on a stub shaft 43, carried by a suitable support 44, which also is carried by the upper end of the shaft 20.

70 The hub of the gear 42 is connected to a shaft 45 by a suitable coupling 46. The shaft 45 has a bevel gear 47 in mesh with a bevel gear 48 mounted on a sleeve 49 rotatively mounted on an axle 50 carried by suitable bearings 51 supported by the main frame.

75 The outer end of the sleeve 49 is provided with a hand wheel 52. Rotation of the hand wheel 52 causes the sleeve 49 to be rotated, and in turn the shaft 45 through the bevel gears 47 and 48, and in turn the bevel gears 37 and 40, which in turn will cause the screw threaded shaft 34 to be rotated.

80 The inner end of the shaft 35 is provided with a bevel gear 53 designed to mesh with the lower one of a double set of bevel gears 54 rotatively mounted on the sleeve formed by the hubs of the gears 37 and 40. The upper one of the bevel gears 54 is in mesh with a bevel gear 55 mounted on the inner end of the sleeve 56 rotatively mounted on the shaft 45.

85 The rear end of the sleeve 56 is provided with a bevel gear 57 designed to mesh with the bevel gear 58 mounted on a sleeve 59 carried by the shaft 50. The outer end of the sleeve 59 is provided with a hand wheel 60 by means of which the said sleeve 59 is rotated and in turn the bevel gears 57 and 58, and the sleeve 56, which in turn will rotate the bevel gears 55 and 54 and the screw threaded shaft 35 through the bevel gear 53, so that the said shafts may be operated either simultaneously or independently.

90 Slidably mounted on each of the shafts 34 and 35 is a block 61 which is also screw threaded and provided with downwardly extending members 62 having rollers 63 at their lower ends to engage the side faces of the arms 31 to prevent torsional movement of said 95 blocks as the shafts 34 and 35 are rotated. It will readily be seen that rotation of said shafts will cause the blocks to move longitudinally of said shafts.

98 Each of the blocks 61 is provided with outwardly projecting pins 64, each of which is provided with a link 65, said links having their outer ends pivotally connected to brace arms 66 by a pivot member 67. The free ends of the brace arms 66 are pivotally connected to blocks 68 carried by the disk 22.

103 Depending from each of the pivots 67 is a link 69, the lower end of which is designed to support the scraper blade 70. The members 65 and 66 are of such length that when the arms 31 are arranged either transversely or diagonally with the main frame, the links 69 will be supported outside of the frame members 10. The lower ends of the links 65

are connected to the scraper blade 70 by pivot members 71.

By this arrangement it will be seen that if the blocks 61 are moved outwardly, then the pivot member 67 will be lowered, which will cause the blade 70 to be lowered; or if the blocks 61 are moved inwardly, said blade will be elevated; or if one of the block members is moved outwardly and the other one inwardly, then one end of the blade will be elevated and the other one lowered; or if any one of the blocks 61 is operated, then one end of the blade 70 will be elevated or lowered. The blade 70 is controlled by the hand wheels 52 and 60 before described.

Said blade 70 is adapted to be elevated and lowered when the head 21 is in any of its pivoted positions of movement on account of the bevel gear arrangement above described.

Mounted to the back face of the central portion of the blade 70 is a universal joint 72 comprising a bracket 73 having a vertical pin 74 to which is pivotally connected a knuckle 75 having horizontal pin 76. A shaft 77 is pivotally connected to the pin 76 and rotatively mounted in a triangularly shaped frame 78.

The side members of the frame 78 are provided with rearwardly extending beams 79 pivotally connected to the flanges 16 by pivot members 80 pivotally connected to the flanges 16 by horizontal bolts 81, and pivotally connected to the members 79 by vertical bolts 82. The bolts 81 are mounted in the flanges 16 at points considerably above the member 72 when the lower edge of the scraper blade is in engagement with the ground surface.

Each end of the scraper blade 70 is provided with a universal joint 83, each of which is connected to a tubular brace member 84. The said brace member 84 is provided with a series of openings 85 and designed to telescopically receive a brace member 86. The brace members 86 are pivotally connected to the bolts 81 by universal joint members 87. A pin 88 is provided for each of the tubular members 84, whereby the said members 84 and the co-acting members 86 may be adjusted longitudinally, and when adjusted will firmly retain the scraper blade in its adjusted position against angular movement above the pivotal axis of the head.

On account of the universal joints 72, 83 and 87 it will be seen that the blade 70 may be elevated or lowered when the said blade is placed in any of its angular positions of movement, and that the said blade is always free to move from one position to the other.

It will further be seen that the beams 79 and the frame 78 form a rigid yoke through which a large portion of the power applied to the blade is transmitted. Said yoke holds the blade against lateral movement relative to the advance of the machine, and at the same time permits free tilting movement of

the ends of the blades, and also raising and lowering movement.

On account of the bolts 81 being located a considerable distance above the member 72, it will be seen that a considerable amount of downward thrust is applied to the blade, which applies a considerable amount of force necessary to advance the blade forwardly and to hold it to the ground surface, thereby eliminating the necessity of supporting other mechanism by the blade for this purpose, and at the same time providing means whereby the blade may be easily elevated by the manually controlled mechanism above described.

When it is desired to adjust the angular position of the blade about its vertical axis, the operator grasps the lever 29 and withdraws the pin 26 from the disk 22, and at the same time withdraws the pins 88 from the adjustable brace members, after which the head 21 may be swung about its vertical axis and carries with it the blade 70, it being assumed, of course, that the blade is moved to an elevated position above the ground surface.

After the blade has been adjusted to the desired angular position, the pin 26 is again reset and the pins 88 placed in corresponding openings in the members 84 and 86. It will then be seen that the blade 70 is adjusted against angular movement by the braces 84 and 86, and the head adjusted against angular movement by the pin 26. At the same time the blade 70 is supported to move freely upwardly or downwardly, or to have its ends adjusted in a vertical plane either simultaneously or independently, by the hand wheels 52 and 60.

One advantage of my device lies in the fact that all of the mechanism for supporting and swinging the scraper blade is mounted and supported above the frame member, so that all of the space between the upper edge of the blade and the lower surface of the frame may be utilized for elevating and lowering the blade, thereby providing means whereby a large amount of vertical adjustment may be obtained, and at the same time provides a large space between the blade and the front wheels and the under surface of the frame through which trash and dirt in front of the scraper blade may be moved.

Another advantage of my construction lies in the fact that the mechanism carried by the supporting head is supported a considerable distance above the frame member and above the dust and dirt created by the blade, thereby eliminating, to a large extent, the trouble due to wear and clogging of these parts.

A further advantage of my construction lies in the fact that the vertical tilting of the blade may be easily accomplished by the hand wheels regardless of the angular position of the blade.

I claim as my invention:

1. A grader comprising a horizontal supporting frame, a shaft projecting upwardly from the central portion of the top of said frame, a supporting head rotatively mounted on said shaft having laterally projecting arms, a scraper blade carried by said arms and beneath said head and supporting frame, and means supported at one end of said frame for simultaneously or independently raising and lowering the ends of said blade when the head is in any of its pivoted positions of movement. 70
2. A grader comprising a horizontal supporting frame, a shaft projecting upwardly from the central portion of the top of said frame, a supporting head rotatively mounted on said shaft having laterally projecting arms, a scraper blade carried by said arms and beneath said head and supporting frame, and hand actuated means carried by one end of said frame for simultaneously or independently raising and lowering the ends of said blade when in any of its pivoted positions of movement. 75
3. A grader comprising a horizontal supporting frame having an upwardly extending shaft on its upper surface, a scraper blade beneath said frame, a head pivotally mounted on said shaft having laterally extending arms, a screw threaded shaft carried by each of said arms, link devices operated by the rotation of each of said screw threaded shafts for elevating and lowering said blade, a pair of horizontal sleeves in common alinement arranged transversely above said frame, a longitudinal horizontal shaft, a longitudinal sleeve, bevel gears for operatively connecting one of the first said sleeves with said longitudinal shaft, bevel gear devices for transmitting power from said horizontal shaft to one of said screw threaded shafts, bevel gear devices for transmitting motion from the other one of said transverse sleeves to said longitudinal sleeve, and bevel gear devices for transmitting motion from said longitudinal sleeve to the other one of said screw threaded shafts. 80
4. In a device of the class described, a frame member having spaced horizontal plates one above the other, a post rigidly supported by said plates and projecting upwardly therefrom, a head rotatively mounted on said post having at its lower end a disk provided with vertical openings, a vertical lock pin slidably mounted in said horizontal plates designed to enter one of the openings of said disk, a rock shaft, a rock arm for operatively connecting said shaft with said vertical locking pin, an actuating lever for said rock shaft, and a spring for yieldably retaining said lever in either of its limited positions of swinging movement. 85
5. In a device of the class described, a supporting frame, an upright shaft, a head rotatively mounted thereon having laterally extending arms, a shaft rotatively mounted on each of said arms, a bevel gear for each of said shafts, a sleeve rotatively mounted on said vertical shaft having a bevel gear at each end, the lower one of which is in mesh with one of the first said bevel gears, a second sleeve rotatively mounted on the first said sleeve having a bevel gear at each end, the lower one of which is in mesh with the other one of first said bevel gears, a horizontal shaft, a bevel gear thereon in mesh with one of the upper ones of said bevel gears, a sleeve on said horizontal shaft, a bevel gear on said sleeve in mesh with the other one of said upper bevel gears, and means for independently rotating said horizontal shaft and said horizontal sleeve. 90
6. A grader comprising a supporting frame, a shaft projecting upwardly from the central portion of the top of said frame, a supporting head rotatively mounted on said shaft having laterally projecting arms, a scraper blade carried by said arms and beneath said head and supporting frame, means supported at one end of said frame for simultaneously or independently raising and lowering the ends of said blade when the head is in any of its pivotal positions, adjustable braces connecting the ends of said blade with said frame, and means for locking said head and braces in corresponding positions. 95
7. A grader comprising a supporting frame having an upwardly extending shaft on its upper surface at a point intermediate its ends, a scraper blade beneath said frame, a head pivotally mounted on said shaft having laterally extending arms, a screw threaded shaft carried by each of said arms, link devices operated by the rotation of each of said screw threaded shafts for elevating and lowering said blade, and means on one end of said frame for independently or simultaneously operating said screw threaded shafts for elevating and lowering said blade when said head is in any of its operative positions. 100
8. A grader comprising a supporting frame, a shaft projecting upwardly from the central portion of the top of said frame, a supporting head rotatively mounted on said shaft having laterally projecting arms, a scraper blade carried by said arms and beneath said head and supporting frame, a pair of hand wheels supported on one end of said frame, and means for operatively connecting said hand wheels for the ends of said blade, whereby operation of either of said hand wheels will cause a corresponding end of said blade to be elevated and lowered when the head is in any of its operative pivotal positions. 105
9. A grader comprising a supporting frame, a blade beneath the said frame, a head supported thereon adapted to swing about a vertical axis and having laterally projecting 110

arms near its upper end, a horizontal screw threaded shaft rotatively mounted on each of said arms, a block slidably mounted longitudinally of each of said shafts and operated thereby, an outwardly extending link pivotally connected to each of said blocks, a second link pivoted to the outer end of each of the first said links, the last said links having their inner ends pivoted to said head near its lower end, a vertical link having its upper end pivotally connected to the pivotal connections of the first and second said links, the lower ends of the last said links being connected to corresponding ends of said blade, and means for operating said screw threaded shafts.

10. A grader comprising a supporting frame, a blade beneath the said frame, a head supported thereon adapted to swing about a vertical axis and having laterally projecting arms near its upper end, a horizontal screw threaded shaft rotatively mounted on each of said arms, a block slidably mounted longitudinally of each of said shafts and operated thereby, an outwardly extending link pivotally connected to each of said blocks, a second link pivoted to the outer end of each of the first said links, the last said links having their inner ends pivoted to said head near its lower end, a vertical link having its upper end pivotally connected to the pivotal connections of the first and second said links, the lower ends of the last said links being connected to corresponding ends of said blade, and means carried by one end of said supporting frame for operating said screw threaded shafts.

11. A grader comprising a supporting frame, a supporting head rotatively mounted thereon, a scraper blade supported beneath said frame and beneath said head, means carried by said head for elevating and lowering the ends of said scraper independently, a pair of hand wheels supported on one end of said frame, and means for operatively connecting each of said hand wheels with one of said blade elevating means, whereby operation of either of said hand wheels will cause the corresponding end of said blade to be elevated and lowered when the head is in any of its operative pivotal positions.

12. A grader comprising a supporting frame, a supporting head rotatively mounted on the upper central portion of said frame to rotate about a vertical axis, a scraper blade carried beneath said frame and beneath said head, means carried by said head for supporting said blade and for elevating and lowering the ends of said blade independently, and hand actuated means carried by one end of said frame for operating said blade elevating and lowering means either simultaneously or independently when the said head is in any of its operative pivotal positions of movement.

13. A grader comprising a supporting frame, a head rotatively mounted on the central portion of said frame to rotate about a vertical axis, said head having laterally projecting arms, a scraper blade carried by said arms and beneath said head and supporting frame, a pair of hand wheels supported on one end of said frame, and means for operatively connecting said hand wheels with the ends of said blade, whereby operation of either of said hand wheels will cause the corresponding end of said blade to be elevated and lowered when the head is in any of its operative pivotal positions.

14. A grader comprising a supporting frame, a supporting head rotatively mounted on the central portion of said frame about a vertical axis and having laterally projecting arms, a scraper blade supported beneath said frame and beneath said head, means for operatively connecting the ends of said blade with corresponding ends of said arms, and means supported at one end of said frame for simultaneously or independently raising and lowering the outer ends of said arms when the head is in any of its pivotal positions.

15. A grader comprising a supporting frame, a supporting head rotatively mounted on the central portion of said frame about a vertical axis and having laterally projecting arms, a scraper blade supported beneath said frame and beneath said head, means for operatively connecting the ends of said blade with corresponding ends of said arms, means supported at one end of said frame for simultaneously or independently raising and lowering the outer ends of said arms when the head is in any of its pivotal positions of movement, and adjustable braces connecting the ends of said blade with said frame.
